FIG. 1.

FIG. 2.

FIG. 3.

FIGURE 1 is a front perspective view of a console cabinet or the like, showing our design;

FIGURE 2 is an elevational view of the side opposite that shown in FIGURE 1; and

FIGURE 3 is a top plan view thereof.

FIGURE 4 is a front perspective view of a modified form of the console cabinet or the like of FIGURE 1;

FIGURE 5 is an elevational view of the side opposite that shown in FIGURE 4; and

FIGURE 6 is a top plan view thereof.

FIGURE 7 is a front perspective view of another modified form of the console cabinet or the like of FIGURE 1; and

FIGURE 8 is an elevational view of the side opposite that shown in FIGURE 7.

FIGURE 9 is an enlarged perspective view of one of the side panels wherein the handle member is shown in raised position and in greater detail.

The back of the console cabinet or the like is plain and unornamented. The dominant features of our design reside in those portions shown in full lines on the drawings.

We claim:

The ornamental design for a console cabinet or the like, as shown and described.
